UNITED STATES PATENT OFFICE.

CHARLES S. COLE, OF BRIDGEPORT, CONNECTICUT.

GASOLENE-ENGINE.

No. 906,773.

Specification of Letters Patent.

Patented Dec. 15, 1908.

Application filed December 18, 1907. Serial No. 406,977.

To all whom it may concern:

Be it known that I, CHARLES S. COLE, a citizen of the United States, and resident of Bridgeport, in the county of Fairfield and State of Connecticut, have invented certain new and useful Improvements in Gasolene-Engines, of which the following is a specification.

My invention relates to motors or engines 10 and more especially to that class known as gasolene engines, and is of the same general type as that shown in my prior patent #724,261-dated March 31st, 1903.

The invention further consists of certain 15 improvements upon the above type of machines which will better adapt it to the use of gasolene, and insure improved results.

The engine is especially designed for automobile use and would preferably be operated 20 in a series of two or more, but is obviously equally practical for other uses, as for instance motor cycles, launches, and likewise stationary work.

It is the objects of my invention to simplify, cheapen and generally improve the construction of engines of this class; to include 25 an improved form of combined ported piston and valve for controlling the supply of fuel to the cylinder in a way to start or stop the engine, or to operate it in either a forward or backward direction; to provide a reciprocating fuel chamber, with means for introducing fuel thereto, and having suitable ports for passing said fuel into a combustion 30 chamber, where it is fired in a way to operate the piston and crank shaft, and finally to provide means for exhausting the exploded products into the atmosphere.

With the above objects in view my invention resides and consists in the novel construction and combination of parts shown upon the accompanying two sheets of drawings forming a part of this specification, upon which similar characters of reference 40 denote like or corresponding parts throughout the several figures and of which—

Figure 1, is a central vertical longitudinal sectional view through my improved engine, showing the cylinder, piston, connecting rod, 50 engine shaft, etc. Fig. 2, is a similar section of my engine with the piston and other movable parts in a different position. Fig. 3, shows a cross sectional plan view of the cylinder and piston taken on line 3-3 of Fig. 2 and as if the mixing chamber and valve were removed. Fig. 4, is a similar

sectional plan view of the piston 16 taken on line 4-4 of Fig. 2, and as seen from the opposite direction of Fig. 3. Fig. 5, is a detached perspective view of the valve seated in the piston, for controlling the operation of the engine, and Fig. 6, is a detail section of a portion of piston and connecting rod as seen in Figs. 1 and 2, but with rod in different position.

Referring in detail to the characters of reference employed to designate the corresponding parts in the several figures of the drawings, 65 10 represents the engine body which as shown may be preferably formed in two parts and secured together as by means of bolts.

11 is a chamber, within the lower part of body to accommodate the crank shaft 12 and rod 13 movably mounted therein. This chamber also serves as a receiver for fuel, 70 which is introduced from and through any suitable source, as for instance a pipe 14.

15 indicates a cylinder that is arranged at a right angle to the crank shaft and is preferably formed integral with the upper part 80 of engine body, which is bored to receive a reciprocating piston 16 that is pivotally connected with the crank rod 13 by means of a pin 17. A second and smaller cylinder 18 is formed in the extreme upper reduced end 85 of the body having its lower end portion extending down into the before mentioned piston cylinder. This smaller cylinder 18 is in alignment with the larger cylinder and serves to form a guideway for a cylindrical 90 mixing chamber 19 secured to the piston 16 as by means of bolts 20, and adapted to reciprocate therewith.

The piston comprises a cylindrical body 15 fitted to reciprocate in the bore of the cylinder and having an internal flange 21 forming a shoulder against which a head 22 fitted within the upper end of piston, is seated. This head may be secured in place by means of the before mentioned bolts 20 and contains a semicircular recess 23 upon underside, against which the transverse cylindrical end portion 24 of rod is fitted. This end is provided with pockets 25 and 26 upon opposite sides, which are designed to communicate with the ports 27 and 28 to pass charges of fuel therethrough from the fuel chamber 11 to the mixing chamber 19. Within the top of the head 22 is formed a circular recess 29 the annular portion of 110 which is covered by flange 30 of the cylinder 19. Within this recess is fitted a disk valve

31 designed to be rotated therein and having a port 32 therethrough that may be adjusted to register with either of the ports 27 or 28. This valve is provided with a central shoul-
 5 dered stem 33, by means of which it is rotated to shift the position of the said port 32 with relation to the ports 27 and 28 in a manner to open and close the same. The said stem 33 of valve is slidably fitted in a shoul-
 10 dered tube 34 in a way to be operated thereby, and is rotated therein. The tube is pro-
 vided with a rounded end portion jour-
 naled in a bearing in end of smaller cylinder
 15 10 and is provided with a suitable handle 35
 by means of which it may be manually oper-
 ated from the exterior of engine, to operate
 the same. On opposite sides of the upper
 portion of the reciprocating mixing chamber
 20 19 is provided ports 36 which register with
 similarly located ports 37 in opposite sides
 of the upper and smaller cylinders 18 which
 ports when communicating admit cold air
 25 from the exterior to the mixing chamber.
 This air is thus obviously introduced when
 the piston and connected ports are in their
 uppermost position and when the previously
 introduced charge is being compressed within
 30 the combustion chamber 38. These ports
 36 are also designed to register with ports 39
 in lower part of cylinder to pass the mixture
 from mixing chamber to the combustion
 chamber 38, when piston is in lowered position
 35 or at end of stroke. When the piston is
 in the above position it will have uncovered
 the exhaust ports 40 so as to allow the ex-
 ploded gases to escape from the cylinder,
 causing a vacuum therein that insures the
 mixture quickly entering the cylinder
 through the ports 36 and 37 before described.
 40 The operation of my improved gas engine
 with the controlling valve set as shown in the
 drawings is as follows:—With the downward
 travel of the piston and the connected opera-
 45 tion of the crank shaft 12 caused by the ex-
 plosion of fuel in chamber 38, the rod 13 is
 rocked to and from the position shown in
 Fig. 6, in a way to admit a charge of fuel
 from the chamber 11, through the ports 26
 50 and 32 to the chamber 19 where the fuel
 may be further mixed with previously intro-
 duced cold air. When the piston and con-
 nected parts reach the end of the downward
 stroke the ports 36 will register with the
 55 ports 39 as shown in Fig. 2, in a way to allow
 the mixture to escape into the firing cham-
 ber 38. The return movement of the piston
 obviously tends to compress the mixture in
 the firing chamber which becomes very
 60 much reduced in area as shown in Fig. 1, and
 smaller than the interior of the mixing cham-
 ber. While in this position the charge is
 fired in the usual way and through the introduc-
 tion of a spark produced in part by the
 65 plug 41 which explosion drives the piston
 down to the end of the stroke where the ex-

haust escapes through the ports 40. Simulta-
 neously with the firing as just explained
 the before mentioned ports 36 and 37 are in
 alinement, to admit a small quantity of cold
 air into the chamber as before referred to.

The foregoing operation applies to the for-
 ward drive of the engine, that is in direction
 of arrow shown in Fig. 1, and includes the
 use of the ports 26 and 28. It will be appar-
 ent however, that a reversal of the engine,
 70 would be obtained by a reverse positive ro-
 tation of the engine in a reverse direction
 after the valve had been reversed which is
 effected through a half turn of the handle 35
 which means the shifting of the port 32 from
 80 above the port 28 to above the port 27 on
 opposite side. This movement of the valve
 permits the fuel to come up through the
 ports 25 and 27 on the opposite side during
 the downward movement of the piston. It
 85 is also possible by shifting this valve to an
 intermediate position, to cut off both ports
 in a way to stop the engine entirely. It will
 therefore be seen that the engine is entirely
 90 controlled by the valve and requires but the
 usual preliminary positive rotating to start
 or reverse it and can be driven forward or
 backward fast or slow as occasion may re-
 quire.

Having thus described my invention what
 I claim and desire to secure by Letters
 Patent is:—

1. In a gasolene engine the combination
 of a cylinder, a reciprocating piston, a cham-
 ber carried by the piston, and a rotary valve
 100 located within the cylinder to control the
 supply of fuel to said chamber.

2. In a gasolene engine, the combination
 of a cylinder, a reciprocating piston, a mov-
 able fuel chamber, and a rotary valve located
 105 within the cylinder to control the supply of
 fuel to said chamber.

3. In a gasolene engine, the combination
 of a cylinder a reciprocating piston mounted
 therein, a mixing chamber carried by the pis-
 ton and having ports for the introduction of
 110 air and fuel and a rotary valve mounted
 within the piston to govern the supply of fuel
 to the chamber.

4. In a gasolene engine, the combination
 of a cylinder provided with air inlets, and ex-
 haust ports, a reciprocating piston mounted
 within the cylinder, a mixing chamber car-
 ried by the piston and having ports to regis-
 ter with said air inlet ports, a valve mounted
 120 within the piston to govern the supply of fuel
 to the mixing chamber, and means for pass-
 ing the said mixture into the firing chamber
 of the cylinder.

5. In a gasolene engine, the combination
 of a cylinder, having a reduced portion with
 air inlet ports, a reciprocating piston mount-
 ed in the cylinder having fuel supply ports
 therethrough, a mixing chamber carried by
 125 the piston and adapted to operate within the
 130

- reduced end of the cylinder and provided with ports on either side adapted to register with the respective ports through the cylinder with each complete forward and return movement thereof and a valve mounted within the piston to open and close the supply ports through the piston.
6. In a gasoline engine, the combination of a cylinder, a reciprocating piston mounted therein provided with ports; a mixing chamber carried by the piston, a rotary valve mounted in the piston, and means exterior of the cylinder for operating the valve to open and close the ports through the piston and to control the supply of fuel to the mixing chamber.
7. In a gasoline engine, the combination of a cylinder having a reduced end portion, a reciprocating piston mounted in the cylinder, a rotary valve mounted in the piston, a mixing chamber carried by the piston and adapted to operate within the reduced end of the cylinder, a telescopic stem connection for the valve whereby the same may be operated from the exterior of the cylinder.
8. In a gasoline engine, the combination of a cylinder, a reciprocating piston mounted therein having oppositely located ports, a connecting rod pivotally connected to the piston and having ports on either side of its connected pivotal end portion to alternately register with the ports of the piston, a rotary valve mounted in the piston, a movable mixing chamber adapted to cover the valve to movably hold it in place, and means exterior of the cylinder for adjusting said valve.
9. In a gasoline engine, the combination of a cylinder having a reduced cylindrical end portion, a reciprocating piston mounted in the cylinder, a cylindrical mixing chamber carried by the piston and operating in the reduced portion of the cylinder, air inlet ports in the reduced portion of the cylinder, ports in the mixing chamber adapted to register with the air inlet ports, a rotary valve carried by the piston to govern the supply of gas to the mixing chamber.

Signed at Bridgeport, in the county of Fairfield, and State of Connecticut, this 12th day of December, A. D., 1907.
